UNITED STATES PATENT OFFICE.

HARRY W. YOUNG, OF MILWAUKEE, WISCONSIN.

TIMER.

Application filed September 21, 1923. Serial No. 663,984.

This invention relates to improvements in timers.

It is the object of this invention to provide a novel, simple and improved timer mechanism which can be constructed at small expense and can be provided with an anti-friction support for its traveling contact member more cheaply than any other timer of which I have knowledge.

10 Timing devices or commutators for controlling the ignition circuits of internal combustion engines commonly include a shell provided with a plurality of stationary contacts and a traveling contact member arranged for movement with respect to said shell in operative relation to the stationary contacts. The arrangement is usually such that a spring or springs press the movable contact into engagement with the stationary contact in order to ensure the maintenance of these parts in operative relation for current transmission. In addition to the springs, it is quite generally customary to provide pivotal mountings for the movable contacts so arranged as to permit the springs to act upon such contacts to press them in the direction of the stationary contacts. The present invention contemplates an improved support for the movable contact whereby the movable contact is wholly supported by the spring which impels it in the direction of the stationary contact. In such a mounting it is very desirable that the movable contact be prevented from angular movement with respect to its actuating member. Consequently, it is a further object of this invention to provide a resilient support for a movable contact which will not be angularly yieldable.

40 In the drawings:

Figure 1 is an axial sectional view through a device embodying this invention and exemplifying a preferred construction thereof.

Figure 2 is an elevational view of the interior of the timer shell showing a fiber raceway and electric contacts imbedded therein.

Figure 3 is a view similar to Figure 2 and illustrating the movable contact disposed operatively within the shell.

50 Figure 4 is a detail section taken on line 4-4 of Figure 3 and illustrating on an enlarged scale a modified construction for the spring and spring support shown in Figure 3.

55 Figure 5 is a view similar to Figure 1 il-

lustrating a modified support for the movable timer contact.

Figure 6 is a detail section taken on line 6-6 of Figure 9.

Figure 7 is a plan view of the head of one 60 of the stationary contact bolts.

Figure 8 is a side elevation of the contact bolt illustrated in Figure 6.

Figure 9 is an external elevation of the timer shell.

65 Figure 10 is a view, in partial section, of a further modified timer construction illustrating a slightly different brush from that shown in Figures 1 and 5 and illustrating a modified shell.

70 Figure 11 is a front elevation of the shell illustrated in Figure 10 with portions broken away to expose the interior.

75 Figure 12 is a detail view, in front elevation, of the brush mechanism shown in Figure 10.

Figure 13 is a side elevation of the brush mechanism shown in Figures 10 and 12.

80 Like parts are identified by the same reference characters throughout the several views.

A distributor shaft 10 of the usual type has a threaded end portion upon which the retaining nut 11 is receivable to secure upon the shaft the sleeve 12 which supports the brush mechanism in the usual manner. The 85 sleeve is keyed to the shaft by means of a pin 13 carried by a cap 13' and held in place by nut 11.

In the present device, sleeve 12 is provided at its inner end with a radially projecting 90 ear 14 to which a resilient support for the movable contact is connected. This support will preferably take the form of a resilient member or spring 15 of substantially oval contour and including an aperture 16 in an 95 intermediate portion adapted to receive the sleeve 12. Before the spring is hardened, a portion thereof may be bent, as indicated at 17, to support a rolling contactor device hereinafter to be described.

100 The means whereby the spring is secured upon sleeve 12 is preferably simple. One or more rivets 18 passed through a portion of the spring and through the ear 14 will ordinarily serve to afford a rigid connection 105 between these parts. The arrangement is such that the free end of the spring (including the reversely bent portion 17) will be axially movable and the aperture 16 in the spring will be sufficiently large to permit the 110

spring to move without friction upon sleeve 12.

In the event that further security in the positioning of the spring with reference to sleeve 12 is desired, the number of rivets 18 5 may be multiplied or else the spring may be formed with an integral rib 19, as illustrated in Figure 4, which rib may be receivable into a suitable recess 20 in ear 14. If the construction illustrated in Figure 4 is adopted, the spring will, in effect, be keyed to ear 14 10 against angular movement about the axis of rivet 18.

Carried by the reversely bent portion 17 15 of spring 15 is a bolt 22 upon which are mounted the complementary cones 23 and 24 which, together, comprise the inner race for the anti-friction balls 25. Bolt 22 is threaded to receive a nut 26 by means of 20 which cones 24 and 25 may be securely clamped together and fastened to the portion 17 of spring 15. The contact proper comprises a spherically surfaced roller 27 of 25 annular form having an internal groove 28 providing an outer race for balls 25. Thus, the roller 27 is connected through anti-friction means with a resilient support 15.

The timer shell is designated in its entirety by reference character 30. It includes 30 an annulus 31 and a fiber plate or disk 32 for the support of the relatively fixed contacts. Annulus 31 will preferably be formed from sheet metal. A strip of such metal will be subjected to a preliminary 35 stamping operation to form the shoulder 33. The shouldered strip will then be bent to annular form as indicated in the drawings, its ends being joined at 34 by means of the fitting 35 which may be secured to each of 40 the ends of the strip by means of rivets 36. It will be understood that the contacts carried by the shell are only relatively stationary, the shell being rotatable adjustable upon its axis through the medium of a suitable 45 control connected with the sleeve portion 37 of fitting 35.

It will be further understood that the timer shell 30 is carried by a relatively fixed 50 part of the engine in a mounting permitting of its rotative adjustment as aforesaid. The mounting of such shells and the means provided for their rotative adjustment are too common to require further explanation here.

The annulus 31 having been formed preferably 55 from a strip of metal as aforesaid to provide shoulder 33, the suitably apertured fiber disk 32 is now inserted into the end of annulus 31 to a seat abutting the annular shoulder 33 thereof. The outer margin of the annulus is next upset radially inwardly as shown at 41 to retain the disk 32 60 permanently in place. The disk may be provided with a central opening 42 of sufficient size to afford clearance for the nut 11 65 upon the commutator shaft 10.

In suitable apertures at spaced points in the dielectric disk 32 are preferably disposed stationary contact members 45 each of which preferably comprises a bolt having a threaded shank 46 an frusto conically tapered head 47 and one or more radially extending wings 48 adapted to be imbedded in the material of the dielectric disk 32 to secure the contact bolt 45 against rotation. When the contact devices 45 have been 70 properly positioned within the dielectric disk 32 at equally spaced angular distances about the circumference of a common circle, each of the shank portions 46 of devices 45 may be provided with a knurled nut 49 75 adapted to retain in operative contact with each shank 46 and ordinary connecting device 50 at the end of a suitably insulated electric contactor, here represented at 51. The nuts 49 may also retain in place a cap 80 85 52, preferably of dielectric material, which is provided with suitable apertures for the shanks 46 of contact devices 45 and is so formed as to provide a closure for the opening 42 in disk 32. 90

The interior surface of disk 32 will be so finished as to leave said disk and the heads 47 of contact devices 45 in a common plane, thereby providing a raceway for the rolling contactor 27. It will be obvious that as 95 the shaft 10 rotates, the rolling contactor 27 will be carried therewith about the race provided on the vertical surface of dielectric disk 32. At properly spaced intervals in the course of such rotation, the rolling 100 contactor 27 will traverse each of the relatively fixed contacts 45, thereby affording communication between the conductor terminals 50 and the ground which, for the purpose of this description, may be assumed 105 to be the shaft 10. Inasmuch as the spherically surfaced rolling contactor 27 will only have point contact with the race at any given time, it will be obvious that the pressure of the spring support 15 will be confined to a comparatively very small area and a comparatively light spring will thereby 110 serve to maintain the rolling contactor in operative position upon the race.

The embodiment of this invention which 115 is illustrated in Figure 5 is similar in all respects to the device already described with the exception that a different type of support is provided for the rolling contact.

In the Figure 5 construction the resilient 120 support 55 comprises a coiled spring, preferably a helical spiral spring. The sleeve 12' has no ear 14, but in lieu thereof is provided with an aperture at 56 into which a radially bent end portion of spring 55 is 125 inserted. The free end 57 of spring 55 is also bent to a substantially radial position and is threaded to receive a nut 26 corresponding to the nut 26 used upon bolt 22 130 which, in the embodiment under discussion,

is replaced by the spring portion 57. A suitable washer 58 upon the spring serves as a backing against which inner race members 23 and 24 may be tightened through the medium of nut 26.

The operation of the device shown in Figure 5 corresponds substantially with that already described, with more particular reference to the Figure 1 construction. 10 Spring 55 is under axial compression and forces the rolling contactor 27 into point contact with the race provided upon the vertical inner face of the dielectric plate 32. On said race, the contactor 27 traverses successively the several stationary contact devices 45, thereby affording communication successively between such devices and shaft 10, which is here assumed to be grounded in the usual manner.

20 Either of the devices herein disclosed may serve as an operative commutator. Timing may be accomplished more accurately, however, with the device shown in Figure 1 than with the device shown in Figure 5, for the reason that the spring 55, when subjected to the momentum effects developed during commutator action, may yield resiliently in a manner to permit of slight arcuate movements of the rolling contactor 27 with respect to the shaft 10. Such movements are obviously impossible where the flat spring 15 is used, inasmuch as the portions thereof are each flat and have considerable transverse extent and are also widely spaced apart whereby to resist strongly any tendency for the traveling contactor 27 to move arcuately independently of the shaft 10.

25 A further modification incidentally illustrated in Figure 5 may comprise a housing 60 arranged to enclose knurled nuts 49 and provided with apertures through which threaded shanks 46 may be reached by the connectors 50. The housing 60 may be used with or without shaft 52.

The construction illustrated in Figures 10 to 13 differs but slightly from those already described, but is preferred because of its sturdiness and simplicity. The sleeve 12" is provided with diverging arms 62 and 63 to which the spring 65 is connected at its ends by means of rivets 66 or like securing means. The brush roller 27 may correspond in its mounting and general arrangement to that disclosed in Figure 1 and need not be further described except that it will be noted that spring 65 is bent intermediate its ends to provide an eye portion 67 within which stud 22 is received for the support of cones 23 and 24 upon which the ball bearing roller 27 is mounted.

Prior to the assembly of the structure, the spring 65 will be formed to take the position in which it is illustrated in Figure 13. 65 When the timer is assembled, the spring 65 is forced to a vertical plane, including its

riveted ends 66, and is thereby placed under compression tending to maintain it in contact with the race.

While the shell 30' differs slightly in form from the shell 30 heretofore described, its 70 general construction is very similar. Cap 52, however, is preferably omitted and an external cap 60' is fitted frictionally over the shell and is provided with a single aperture 68 through which the several conductors 69 75 leading to the fixed terminals of the timer are threaded.

In order to provide for adjusting the various timers herein disclosed for use in connection with a variety of different spark control levers, I preferably utilize the device best illustrated in Figure 11.

An upstanding ear 70 connected with the timer shell 30' is provided with a threaded aperture to receive a screw member 71 upon 85 which I secure a block 72 having an aperture at 73 to receive connection with the timer adjusting linkage. A lock nut 74 threaded upon screw 71 serves to tighten the screw in any desired position of rotative adjustment. 90

It will be understood that the linkage connecting the timer control lever with the timer shell 30' for its rotative adjustment, as aforesaid, will be attached to block 72 through a pin inserted in opening 73 in the usual manner. If the desired timing range cannot then be accurately secured, it is possible to adjust shell 30' with reference to the manually operated spark control lever by loosening the lock nut 74 and setting screw 100 71 inwardly or outwardly with respect to the supporting ear 70, thereby the angular adjustment of shell 30' is changed.

The simplicity of the construction herein disclosed, the cheapness with which this type of timer can be manufactured, and the evident effectiveness with which it will be operated will be obvious to those skilled in the art.

I claim:

1. In a timer brush, the combination with a sleeve affording spaced points of support, of a spring connected with said sleeve at such points and bent intermediate its ends to form an eye, a stud receivable in said eye, and a brush roller journaled for rotation about said stud.

2. In a timer brush, the combination with a sleeve affording spaced points of support, of a spring connected at its ends with the sleeve at such points and formed intermediate its ends to provide an eye, a bolt threaded through said eye, a device supported from said bolt and providing a bearing race, a roller concentric with said device and providing a complementary race, and anti-friction means interposed between the races of the device and the roller.

3. In a timer brush construction, the combination with a sleeve providing spaced

4

points of support, of a resilient wire connected at its ends with the sleeve at such points and bent intermediate its ends to form an eye, the normal position of said wire being inclined from a radial plane including such points, a stud connected with said wire at said eye and disposed at an angle from said radial plane determined by the position

of said wire, and a roller supported for rotation about said stud. 10

In testimony that I claim the foregoing I have hereunto set my hand at Milwaukee, in the county of Milwaukee and State of Wisconsin.

HARRY W. YOUNG.
